(57) **CLAIM**

I claim the ornamental design for a solar charger, as shown and described.

DESCRIPTION

FIG. 1 is a front perspective view of first embodiment of a solar charger;

FIG. 2 is a front view of a first embodiment thereof;

FIG. 3 is a back view of a first embodiment thereof;

FIG. 4 is a left-side view of a first embodiment thereof;

FIG. 5 is a right-side view of a first embodiment thereof;

FIG. 6 is a top view of a first embodiment thereof;

FIG. 7 is a bottom view of a first embodiment thereof;

FIG. 8 is a front perspective view of a second embodiment of a solar charger;

FIG. 9 is a front view of a second embodiment thereof;

FIG. 10 is a back view of a second embodiment thereof;

FIG. 11 is a left-side view of a second embodiment thereof;

FIG. 12 is a right-side view of a second embodiment thereof;

FIG. 13 is a top view of a second embodiment thereof;

FIG. 14 is a bottom view of a second embodiment thereof;

FIG. 15 is a front perspective view of a third embodiment of a solar charger;

FIG. 16 is a front view of a third embodiment thereof;

FIG. 17 is a back view of a third embodiment thereof;

FIG. 18 is a left-side view of a third embodiment thereof;

FIG. 19 is a right-side view of a third embodiment thereof;

FIG. 20 is a top view of a third embodiment thereof;

FIG. 21 is a bottom view of a third embodiment thereof;

FIG. 22 is a front perspective view of a fourth embodiment of a solar charger;
